ROLL GRINDING MACHINE

Albert G. Belden, Worcester, Mass., assignor to
 Norton Company, Worcester, Mass., a corpora-
 tion of Massachusetts

Application December 24, 1935, Serial No. 56,004.

10 Claims. (Cl. 51—100)

This invention relates to a grinding machine, and more particularly to a roll grinding machine having a crowning apparatus for producing a predetermined concave or convex crown on a roll being ground.

5 One of the objects of this invention is to provide a simple, thoroughly practical crowning apparatus for a roll grinding machine for generating a predetermined convex or concave crown on the roll being ground. It is a further object of
 10 this invention to provide a crowning apparatus which is readily adjustable for varying the extent of crown. It is a further object of this invention to provide a roll crowning attachment in a roll grinding machine, in which it is readily adjust-
 15 able for producing either a convex or a concave surface. Other objects will be in part obvious and in part pointed out hereinafter.

This invention accordingly consists in the features of construction, combinations of elements, 20 and arrangements of parts, as will be exemplified in the structure to be hereinafter described, and the scope of the application of which will be indicated in the following claims.

In the accompanying drawing, in which is 25 shown one of various possible embodiments of the mechanical features of this invention;

Fig. 1 is a fragmentary plan view of a grinding machine embodying this invention;

Fig. 2 is a fragmentary cross sectional view, 30 on an enlarged scale, taken approximately on the line 2—2 of Fig. 1;

Fig. 3 is a fragmentary front elevation, on an enlarged scale, of a table traverse mechanism; and

35 Fig. 4 is a fragmentary detail view, showing the connections between the rack and the table.

A roll grinding machine has been illustrated in the drawing, comprising a base 10 having a longitudinally reciprocable work table 11 supported thereon on a pair of spaced flat ways 12 and 13 which mate with a pair of narrower flat ways 14 and 15 on the table 11. The ways 12 and 13 are of sufficient width to allow the ways 14 and 15 on the work table 11 to slide transversely 45 relative to the base through a sufficient distance to take care of the extent of crown desired to be produced on the roll being ground. The work table 11 is arranged to rotatably support a roll 20 on a headstock 21 and a footstock 22.

50 A rotatable grinding wheel 25 is supported on a wheel spindle 26 which in turn is rotatably supported on a transversely movable wheel slide 27.

The wheel slide 27 is arranged to be moved trans- 55 versely relative to the base 10 by a suitable wheel

feeding mechanism which may comprise a half nut 28 depending from the wheel slide 27 and mating with a rotatable feed screw 29 which is journaled in bearing (not shown) in the base 10. The front end of the feed screw 29 is provided with a gear 30 meshing with a gear 31 5 on the inner end of a rotatable shaft 32. The front end of the shaft 32 carries a gear 33 meshing with a gear 34 on a shaft 35 which supports a manually operable feed wheel 36. By rotating the feed wheel 36, the cross feed screw 29 may be 10 rotated to cause the grinding wheel 25 and its supporting slide 27 to move either toward or from the roll 20 being ground.

The grinding wheel 25 and the work table 11 are arranged so that they may be reciprocated 15 longitudinally relative to each other to produce the desired grinding action upon the roll being ground. In the preferred construction, the table 11 is reciprocated by means of a rack-bar 40 which is slidably supported on the base 10. A gear 41 20 meshes with the rack 40 which is arranged to be driven by a power driven mechanism, for example such as that shown in the prior patent to Norton No. 762,838 dated June 14, 1904. Power is applied to rotate a shaft 42 which serves to rotate 25 a clutch member 43 which is arranged to engage either the clutch member 44 or the clutch member 45. A gear 46 is formed integral with clutch member 45. The bevel gears 46 and 47 mesh with a common bevel gear 48 which is supported on a 30 rotatable shaft 49. The shaft 49 may be rotated in either direction by shifting the clutch member 43 either into engagement with the clutch member 44 or the clutch member 45. The shifting of the clutch member 43 is preferably accomplished 35 automatically by means of adjustable dogs (not shown) on the table 11 which engage a reversing lever 50. The reversing lever 50 operates through a load and fire mechanism 51 to shift the clutch 40 member 43 automatically and in timed relation with the table movement to cause the table 11 to move in either direction.

The shaft 49 carries on its inner end a gear 53 which meshes with a gear 54 mounted on the 45 inner end of a rotatable shaft 55. The front end of the shaft 55 carries a gear 56 which meshes with a gear 57 mounted on the shaft carrying the pinion 41. It will be readily apparent that when the gear 48 is rotated, the rotation thereof 50 will be transmitted through the shaft 49, gear 53, gear 54, shaft 55, gear 56, gear 57, gear 41, to reciprocate the rack 40 relative to the base 10.

A manually operable hand traverse wheel 60 55 is provided on the front of the machine base and

is supported on a shaft 61 carrying a gear 62 meshing with a gear 63 supported on a shaft 64. The shaft 64 in turn supports the gears 57 and 41 so that rotation of the hand wheel may rotate 5 the gear 41 and transmit a longitudinal movement to the rack 40.

In order to disconnect the power mechanism when it is desired to move the table manually, a clutch member 65 is mounted on the shaft 55 and 10 is arranged in the position of the parts illustrated in Fig. 2 to permit hand or manual traverse of the table. When it is desired to reciprocate the table automatically by power, a manually operable lever 66 is moved about its pivot 67 toward the 15 front of the machine base to cause an endwise movement of a rod 68 toward the left, as viewed in Fig. 2, which serves to move a yoked member 69 which straddles a groove in the clutch member 65 so as to slide the clutch member endwise into 20 engagement with a clutch member 70 which is formed integral with a gear 56, thereby connecting the gear 54 to rotate the gear 56 which in turn rotates the gear 57, the gear 41, to reciprocate the rack bar 40 under power.

25 To permit the work table 11 to be moved transversely as well as longitudinally on its ways, it is necessary to provide a suitable connection between the rack bar and the table during the crowning operation. A pivot pin 75 is inserted in 30 an aperture 76 in the table 11. The pivot 75 is provided with a downwardly extending projection 77 which is slabbed off on its sides and fits within a transverse slot 78 in the rack bar 40. It will be readily apparent from the foregoing that when 35 the rack bar 40 is reciprocated longitudinally, the projection 77 serves to carry the table 11 in a longitudinal direction and the pivot 75 serves to allow the table 11 to swing as it moves longitudinally and the transverse slot 78 in the rack bar 40 permits the pivot pin 75 to move transversely 40 relative to the rack 40 as the table 11 is moved through an arcuate path in generating a predetermined crown on the roll being ground.

In order that the table 11 may be moved longitudinally and transversely through a predetermined path to generate a predetermined crown on the roll being ground, a pair of forming bars 80 and 81 are pivotally mounted on studs 82 and 83 respectively. The studs 82 and 83 are supported in brackets 84 and 85 which are fixed to the base 10. The outer ends of the forming bars 80 and 81 are supported in brackets 86 and 87. These brackets are fixedly mounted on the base 10 and are provided with adjusting screws 88, 89 55 and 90, 91, by means of which the bars 80 and 81 may be angularly adjusted relative to the base 10.

60 The forming bars 80 and 81 are connected by brackets 95 and 96 fixed to the table 11 and carry pivotally mounted slides 97 and 98 respectively which are shaped to fit and slide along the forming bars 80 and 81. The slides 97 and 98 are pivotally connected to the brackets 95 and 96 respectively by studs 99 and 100. It will be readily apparent from the foregoing disclosure that, as 65 suming the parts to be located as shown in Fig. 1, when the table 11 is reciprocated longitudinally relative to the base 10, the slides 97 and 98 moving along the forming bars 80 and 81 cause a transverse movement of the table 11 relative to the base 10, so that the table moves the roll 20 being ground in an arcuate path to generate a predetermined crown on the periphery of the roll. In the position of the bars as illustrated in Fig. 1, a convex crown will be produced on the roll.

70 75 If the bars 80 and 81 are adjusted by means of

the screws 88, 89, 90 and 91, so that they are parallel with the way 13, then the table 11 will be reciprocated in a straight path and the grinding wheel will grind a true cylinder on the periphery of the roll. If the bars 80 and 81 are adjusted so that their outer ends approach the way 13, then the table will be moved in a path to produce a concave crown on the roll being ground.

5 The operation of this machine is readily apparent from the foregoing disclosure. The forming 10 bars 80 and 81 are adjusted through a desired position to generate a predetermined crown on the roll being ground. The table 11 is then reciprocated either manually by means of the hand wheel 60 or by power rotation of the shaft 42. 15 The pinion 41 serves to reciprocate the rack 40 and the table 11 is caused to move longitudinally, as carried by the rack 40, and transversely, as governed by the forming bars 80 and 81 to grind a predetermined crown on the roll 20. The wheel 20 25 is fed toward the periphery of the roll to grind the same to the required extent.

It will thus be seen that there has been provided by this invention apparatus in which the various objects hereinabove set forth together 25 with many thoroughly practical advantages are successfully achieved. As many possible embodiments may be made of the above invention and as many changes might be made in the embodiment above set forth, it is to be understood that all 30 matter hereinbefore set forth or shown in the accompanying drawing is to be interpreted as illustrative and not in a limiting sense.

I claim:—

1. A grinding machine comprising a base, a 35 rotatable grinding wheel, a transversely movable slide supporting said wheel, a longitudinally movable table having a pair of parallel flat ways thereon, a pair of spaced parallel ways on said base which are wider than the table ways to 40 permit a longitudinal and transverse movement of said table thereon, a rotatable work support on said table, means to feed said slide either towards or from the table, means to reciprocate said table longitudinally, and means to move said 45 table transversely during the longitudinal movement thereof to generate a predetermined crown on a work piece.

2. A grinding machine comprising a base, a 50 rotatable grinding wheel, a transversely movable slide supporting said wheel, a longitudinally movable table having a pair of parallel flat ways thereon, a pair of spaced parallel ways on said base which are wider than the table ways to 55 permit a longitudinal and transverse movement of said table thereon, a rotatable work support on said table, means to feed said grinding wheel slide transversely to grind the work piece to a predetermined size, means to reciprocate said table longitudinally on said ways, and means to move said 60 table transversely on said ways during the longitudinal reciprocation thereof to swing the work support in an arcuate path and generate a predetermined crown on a work piece.

3. A grinding machine comprising a base, a 65 rotatable grinding wheel, a transversely movable slide supporting said wheel, a longitudinally movable table having a pair of parallel flat ways thereon, a pair of spaced parallel ways on said base which are wider than the table ways to 70 permit a longitudinal and transverse movement of said table thereon, a rotatable work support on said table, means to feed said grinding wheel slide transversely to grind the work piece to a predetermined size, means to reciprocate said 75

table longitudinally on said ways, and means including a forming bar to move said table transversely on said ways during the longitudinal reciprocation thereof to swing the work support in an arcuate path and generate a predetermined crown on a work piece.

4. A grinding machine comprising a base, a rotatable grinding wheel, a transversely movable slide supporting said wheel, a longitudinally movable table having a pair of parallel flat ways thereon, a pair of spaced parallel ways on said base which are wider than the table ways to permit a longitudinal and transverse movement of said table thereon, a rotatable work support on said table, means to feed said grinding wheel slide transversely to grind the work piece to a predetermined size, means to reciprocate said table longitudinally on said ways, means including a forming bar to move said table transversely on said ways during longitudinal reciprocation thereof to swing the work support in a curved path, and means to adjust said bar to generate a predetermined crown on a work piece.

5. A grinding machine comprising a base, a rotatable grinding wheel, a transversely movable slide to support said wheel, a work supporting table which is movable longitudinally and transversely on said base, a rotatable work support on said table, means to feed the grinding wheel either toward or from the work piece to grind the same to a predetermined size, means to reciprocate said table longitudinally on the base and means including a forming bar which is arranged to move said table transversely on said base during its longitudinal movement to generate a predetermined crown on the roll being ground.

6. A grinding machine comprising a base, a rotatable grinding wheel, a transversely movable slide supporting said wheel, a longitudinally movable table having a pair of parallel flat ways thereon, a pair of spaced parallel ways on said base which are wider than the table ways to permit a longitudinal and transverse movement of said table thereon, means including a pair of forming bars which are arranged to move said table transversely during longitudinal reciprocation thereof, and means to adjust the angular position of said bars to generate either a convex or concave crown on the periphery of said roll.

7. A grinding machine comprising a base, a rotatable grinding wheel, a transversely movable slide supporting said wheel, a longitudinally movable work supporting table having a pair of spaced flat ways thereon, a pair of spaced flat ways on said base which are wider than the ways on said table to permit a transverse movement of the table during reciprocation thereof, a rotatable work support on said table, means to

reciprocate said table, and means including a pair of spaced adjustable forming bars which are operatively connected to opposite ends of said table to move said table transversely during the reciprocation thereof to generate a predetermined crown on the roll being ground.

8. A grinding machine comprising a base, a rotatable grinding wheel thereon, a transversely movable slide to support said wheel, a longitudinally movable work table supported on said base, a pair of flat ways on said table, a pair of mating flat ways on said base which are of a greater width than the ways on said table so that the table may move transversely relative to the base, a rotatable work support on said table, means to feed said slide to move the grinding wheel either toward or from the work piece, a pair of adjustable forming bars which are operatively connected to move the opposite ends of said table transversely when the table is reciprocated to move said work piece in an arcuate path to generate a predetermined crown on the roll being ground.

9. A grinding machine comprising a base, a rotatable grinding wheel, a transversely movable slide to support said wheel, a longitudinally movable work supporting table having a pair of spaced flat ways thereon, a pair of longitudinally extending flat ways on said base which are wider than said table ways to permit a transverse movement of said table during its longitudinal reciprocation, a rotatable work support on said table, a pair of forming bars adjustably mounted on said base, a slide on each of said forming bars, brackets fixed to each end of said table and pivotally connected to said slide, said parts being arranged so that when the table is reciprocated longitudinally, the forming bars move the ends of said table transversely to move the work piece in an arcuate path to generate a predetermined crown thereon.

10. A grinding machine comprising a base, a rotatable grinding wheel and a rotatable work support which are movable longitudinally and transversely relative to each other, means to feed one of said elements toward and from the other to grind the work piece to the desired extent, a longitudinally movable table supporting one of said elements having a pair of parallel flat ways thereon, a pair of spaced parallel ways on said base which are wider than the table ways to permit a longitudinal and transverse movement of the table and the elements supported thereby, means to reciprocate said table longitudinally, and means to move said table transversely during the longitudinal movement thereof to generate a predetermined crown on the work piece being ground.

ALBERT G. BELDEN.
